UNITED STATES PATENT OFFICE.

OTTO VANSELOW, OF SCHOOLCRAFT, MICHIGAN.

FURNITURE CONSTRUCTION.

1,017,712.

Specification of Letters Patent. Patented Feb. 20, 1912.

Application filed October 2, 1911. Serial No. 652,287.

To all whom it may concern:

Be it known that I, OTTO VANSELOW, a subject of the Emperor of Germany, residing at Schoolcraft, in the county of Kalamazoo and State of Michigan, have invented certain new and useful Improvements in Furniture Construction, of which the following is a specification.

My invention relates to improvements in furniture construction and is especially applicable to such furniture as chairs and the like carried on supports which must be firmly tied and braced together.

The object of my invention, generally speaking, is to provide a tie or brace device of novel and improved form and construction by means of which, for example, the legs of a chair can be firmly tied together, and which is adapted to be placed in a concealed position in a piece of furniture of ordinary construction.

To be more specific, my invention has for its object to provide a metal, preferably steel tie device which can be applied with a minimum cutting to furniture made of wood, which is especially adapted to exert all strains in the same plane which shall have a certain flexibility and adjustability for the purpose hereinafter described, which can be assembled with the other parts of the piece of furniture by a simple, easily performed operation not requiring a high degree of skill, which shall be simple and inexpensive of manufacture, compact in form and adapted to be most securely locked together so as to produce equal tensions as between the parts of the article of furniture which it ties together.

These and such other objects as may hereinafter appear are attained by my invention, a preferred form of which is shown in the accompanying drawing as applied to an ordinary dining room chair.

Figure 1 indicates a chair with my device applied. Fig. 2 is a view on the line A—A of Fig. 1, looking in the direction indicated by the arrows. Fig. 3 is a view of my device in preferred form, as it is assembled in a chair or similar article of furniture. Fig. 4 is a detail sectional view through a chair leg and portions of the rounds, supplied with my device. Fig. 5 is a detail sectional view through one of the connecting members. Fig. 6 is a perspective view of the assembled device as shown in Fig. 3.

Like letters of reference indicate the same parts in the various figures of the drawings.

A is one of the connecting members or coupling elements for the tie rods provided with the opening or passage B and transversely on substantially the same plane with the interiorly screw-threaded and intersecting passage C. In the embodiment of my invention shown in the drawings there are four such devices connected by rods D, each rod being threaded at one end into the threaded passage in one of the connecting members A and its other end extending freely through the intersecting, non-threaded passage B and projecting therethrough, the projecting end of each rod being fitted with a nut E threaded thereon.

As shown in Fig. 4, the connecting members A are embedded in recesses f formed in the outer faces of the legs F of the chair, these recesses being preferably closed by the wooden blocks G. When the chair is provided with the reinforcing or bracing structure adjacent its rungs H, which is a preferred construction, the latter are formed either with grooves h in their under surfaces, as shown in Fig. 4, or with longitudinal perforations extending therethrough from end to end, and the tie rods D lie within these grooves or perforations so as to be effectively concealed.

In putting the chair together the recesses f are made in the outer faces of the legs after which the legs are bored through to form the perforations f', f'' for the tie rods. The coupling elements A are fitted into the recesses f and the tie rods D screwed into the sockets C. Glue is applied to the ends of the rungs H and the rungs slipped over the tie rods. By bringing the legs and rungs together in proper position the free ends of the tie rods D are projected through the perforations B in the coupling elements. The nuts E are then placed on the ends of the tie rods and screwed up as much as is required.

It will be seen that the assembling of the parts of the chair and the reinforcing or bracing structure is a simple operation which can be quickly performed and which does not require a great deal of skill for its performance. It is necessary that the operation should be quickly performed because if much time is wasted the glue on the ends of the rungs sets so that the job has to be

done over again. After the parts of the chair have been thus assembled the nuts E may be adjusted so that the reinforcing structure exerts an equal tension on the legs.

5 If the bracing structure did not have this capacity for ready adjustment it might prove worse than useless as the existence of a tension which is greater between one pair of legs than between the others will result in

10 weakening rather than strengthening the chair. As the coupling elements are disks of comparatively small diameter the legs are very little weakened by the recesses formed to receive these elements. Preferably the

15 tie rods forming the reinforcing structure lie in the same horizontal plane. This is desirable in order that the reinforcing structure should not exert unequal strains on the chair. As the free ends of the rod D pass

20 loosely through the perforations B in the coupling members the reinforcing structure may be made to assume a shape which is not strictly rectangular, as must be the case, for example, when the front legs of the chair

25 are set a little wider apart than the back legs, or vice versa. The comparatively small cross sectional areas of the recesses f and the fact that these recesses are circular makes it easier to both form them and to effectively

30 cover and conceal them with the covering blocks or disks G.

The device of my invention may, of course, be applied to furniture having any number of legs from three upward, and may be used

35 in any desired arrangement, the arrangement in a parallelogram being shown in the drawing merely for convenient illustration. I therefore do not wish to limit my invention to the specific forms, devices or

40 arrangements shown except so far as the same are made specifically limitations in certain of the claims; it being my intention to claim both broadly and narrowly whatever patentable novelty my device may in-

45 volve in view of the state of the prior art.

I claim:

1. The combination with an article of furniture having supporting members and transverse members between the supporting members, of a reinforcing device for the same comprising tie rods which are concealed within the transverse members, and coupling elements for the tie rods, one end of each of the tie rods being secured to a coupling element and the other end passing through another coupling element and being provided on the other side of the same with tension adjusting means.

2. The combination with an article of furniture having supporting members and transverse members between the supporting members, of a reinforcing device for the same comprising tie rods which are concealed within the transverse members and coupling elements for the tie rods arranged within the supporting members, the ends of the tie rods being threaded and one end being secured in a threaded socket in a coupling element and the other end passing loosely through another coupling element and being provided with a nut.

3. The combination with an article of furniture having supporting members and transverse members between the supporting members, of a reinforcing device for the same comprising tie rods which are concealed within the transverse members, and cylindrical coupling elements arranged in bores in the supporting members, one end of each of the tie rods extending through the curved surface of the cylindrical coupling element and being secured thereto, the other end extending from end to end through another cylindrical coupling element and being provided on the other side of the same with tension adjusting means.

OTTO VANSELOW.
